UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A RANGE

Application filed July 10, 1931. Serial No. 40,495. Term of patent 14 years.

To all whom it may concern:

Be it known that I, ARTHUR STOCKSTROM, a citizen of the United States, residing in the city of St. Louis and State of Missouri, have invented a new, original, and ornamental Design for a Range, of which the following is a specification, reference being had therein to the accompanying drawings.

Fig. 1 of the drawings is a perspective view of a range having represented on its face two series of tiles, one series arranged around the

face of the oven doors and the other series around the face of the cooking top portion.

Fig. 2 is an enlarged detailed showing of one of the tiles.

I claim:

The ornamental design for a range substantially as shown and described.

In testimony whereof, I hereunto affix my signature.

ARTHUR STOCKSTROM.
